UNITED STATES PATENT OFFICE.

ERNEST J. BRASSEUR, OF CHICAGO, ILLINOIS, ASSIGNOR TO A. B. DICK COMPANY, OF CHICAGO, ILLINOIS, A CORPORATION OF ILLINOIS.

CARD-REGISTRATION MEANS FOR ROTARY DUPLICATING MACHINES.

Application filed February 4, 1927. Serial No. 165,786.

This invention relates to card registration means for rotary duplicating machines, and more particularly to the delivery of the cards into position for engagement by the printing couple, and to the engagement of the cards by the printing couple, whereby the cards are progressed through the machine and printed.

It has been customary heretofore to have the printing couple, comprising the rotating stencil drum and the coacting impression roller, engage the work while the drum is rotating, and often while the work is moving into position therebetween. This has been satisfactory in a general way when sheets of paper are to be printed, but when cards are supplied to the machine there is apt to be some slippage between the cylinder and the card at the time of engagement, and this slippage, which is not uniform for each card, throws the printing out of alignment on the card, and the quality of the work suffers. Also heavier cards will strike the printing couple sooner than thinner cards, due to the difference in the tangential relations of the upper and lower surfaces of the cards to the peripheries of the stencil drum and roller, and thus the print on cards of different thicknesses will be in correspondingly different positions on the cards. This also renders it difficult, if not impossible, to secure the exact registration of the printing on cards of different thicknesses.

The principal object of this invention is to provide a method of and means for engaging cards, or other work, with the printing couple, whereby exact accuracy of printing registration on the card is obtained; and another object of this invention is to provide means whereby exact printing registration may be obtained on cards of different thicknesses.

A further object of this invention is to provide mechanism of the character referred to, which is simple, efficient and positive in action, and is not apt to get out of adjustment, and yet may be adjusted readily and easily by the operator for cards of different lengths, and to align the cards accurately with the printing lines on the stencil.

Other objects of this invention will be in part obvious and in part pointed out hereinafter.

In accordance with this invention, the mechanism is so arranged that the rotatable

stencil drum is stopped in a certain definite position each revolution in printing direction. Other mechanism, synchronized with the rotation of the drum, is arranged to feed each card so that the front edge of the card will be positioned at rest in a certain definite place between the drum and the impression roller when the cylinder is stopped, irrespective of the thickness of the card. A handle is arranged at the side of the duplicating machine, preferably at the same side as the main crank, which the operator may manipulate readily and easily to release a latch or cradle device, which results in the impression roller snapping upward to engage the card between it and the printing cylinder while neither the card nor the cylinder is in motion. In this way, each card, irrespective of its thickness, is engaged with exactly the same relativity with respect to the cylinder and the stencil sheet thereon, and there is no tendency of the registration to be spoiled or varied due to slippage between the cylinder and the card at the time of engagement, or due to the thickness of the card affecting its position relative to the cylinder when it is engaged by the printing couple. The mechanism is so arranged that when the operator carries the movement of the handle further, the cylinder will be released, so that it can be rotated by the main crank handle to print the card which has been engaged in the printing couple, as aforesaid. Preferably, this additional movement of the roller releasing handle also resets the latch or cradle, so that the roller will be relocked in depressed position until the next card has been advanced into engaging position and the releasing handle operated again to effect the engagement of this next card in the printing couple.

The mechanism which advances the card into position to be engaged by the printing couple is preferably adjustable, so that cards of various lengths may be advanced to exactly the same stationary position for engagement by the printing couple.

Means are also provided for adjusting the cards horizontally with respect to the axis of the printing cylinder, so that the cards may be aligned exactly with the print on the stencil. In this way, there is avoided the necessity of adjusting the stencil sheet on the cylinder if it is found that the printing lines thereon do not print exactly paral-

lel with the horizontal component of the card.

In order that a clearer understanding of this invention may be had, attention is here-
5 by directed to the accompanying drawings, forming a part of this application and illustrating certain possible embodiments of this invention.

Referring to the drawings, Fig. 1 is a side view of a rotary stencil duplicating machine embodying this invention and showing certain hidden parts in dash lines to show their location. The machine is shown with the card feeding means in retracted position and
10 the cylinder approaching its position of stoppage. A card is shown in place prior to its advance into position of engagement by the printing couple. Fig. 2 is a view similar to Fig. 1, but shows in a diagrammatic manner the position of the parts after the roller has been released to effect the engagement of the card between the printing couple and before the cylinder has been released for revolution to carry the card
15 forward and print the same. Figs. 3 and 4 are respectively front and side views of the detail of the connection between the feed table and the lever which moves the same. Fig. 5 is a top view of the machine with the
20 stencil cylinder removed; and Fig. 6 is a diagrammatical illustration of the different relative positions which cards of different thicknesses would assume with respect to the printing cylinder if they were allowed
25 to strike a member of the printing couple before being engaged thereby.

Similar reference characters refer to similar parts throughout the several views of the drawings.

40 Referring to the drawings, 1 designates the printing drum or cylinder which carries the stencil or other printing means. The drum is supported on a shaft 2, which is rotatably carried on the side frames 3 and 4 of the machine. Below the drum is the rubber impression roller 5, rotatably carried on arms 6 pivotally secured to the frame and engaged by springs 7, which tend to pivot the arms 6 upwardly to press the impression roller against the drum, and engage the work therebetween. Levers 8 at opposite sides of the machine are secured to a rock shaft 9, and have their noses 10 above and in engagement with the ends of arms 6 ad-
45 jacent the roller 5. A lever 11, fixed to shaft 9, carries a roller 12 positioned to be depressed by the usual cam 13 on the cylinder. The tail 14 of lever 11 coats with a pivoted stop device, commonly called the
50 roll stop shaft cradle, and designated generally at 15, which normally is held by spring 16 in position beneath the tail 14 of lever 11 to prevent the rocking of the tail 14 downwardly, and thus to hold the roller 12
55 depressed. Means are provided for with-
60

drawing the latch device 15 from beneath lever 11, and at the same time for holding the cylinder stationary in a certain predetermined position, so that the card 17 to be printed is engaged by the printing couple 70 while there is no relative movement between the card and the printing cylinder. Thus, the same exact relative position of each card fed to the print on the cylinder is obtained, irrespective of the thickness of the card. 75 The cylinder and roller are apart as the card moves into position to be engaged by this couple.

By maintaining the cylinder stationary at the times stated, there can be no slippage between the card and cylinder at the time the card is engaged between the printing couple for the subsequent forward delivery and printing.

80 For stopping and holding the cylinder stationary while the card is engaged by the printing couple, the cylinder is provided with a pin 20, fixed at a definite location thereon, which, at a certain position of the cylinder, strikes against and is caught by the hooked end 21 of a lever 22, which is fixed on a rock shaft 23, journaled in the side brackets of the machine. A gear 24 secured to shaft 23 meshes with a gear 25 loose on a shaft 26. Shaft 26 carries a pin 27, which 85 seats in cut out notches 28 in the hub of gear 25, so that shaft 26 may be rotated a certain distance without the pin 27 causing rotation of gear 25. A rock lever 30, pivoted intermediate its ends, as at 31, has one arm 32 adapted to engage and rock cradle 15, and has another arm 33 positioned to be engaged by a pin 34 on an arm 35 which is secured to shaft 26. Shaft 26 may be rotated by means of a lever or handle 36 secured to a protruding end thereof at the side of the machine where the main crank handle is disposed.

100 In operation, the operator first brings the pin 20 into engagement with lever 22 and thereby places the cylinder in a definite stationary position. He then depresses handle 36, thus rotating shaft 26 to swing arm 35, which, through the intervention of rock lever 30, withdraws the cradle 15 from beneath the tail of lever 11 and thus releases the impression roller. Meanwhile, due to the movement of pin 27 in the notches 28 of gear 25, this gear has not rotated and the cylinder has not been released for movement. 110 Thus the card may be moved freely into position between the roller 5 and cylinder 1 while apart, and thereafter the roller is released to engage the card in the printing couple while the cylinder and card are stationary. After this, however, since the pin 27 now engages the sides of notches 28 of gear 25, further depression of the handle 36 causes rotation of gears 25 and 24 and 115 withdraws lever 22 from pin 20, thus per- 120

mitting rotation of the cylinder by means of the main crank 38. Spring 16 automatically returns both the cradle 15 and the roller and cylinder releasing mechanism 5 to normal position, so that the handle 36 must be depressed each time a card is to be engaged and printed.

Since the cylinder is in exactly the same position each time a card is engaged between it and the rubber roller, and the cylinder and card are stationary during the engagement period, the printing on each card will be in exactly the same location, irrespective of the thickness of the card, provided only that the cards be fed to exactly the same place for engagement by the printing couple.

When the cards coming into engagement with the printing couple strike one of these members, the registration of the printing thereon will vary in accordance with the thickness of the card. As an example, reference is made to the diagrammatical showing in Fig. 6, from which it will be seen that a thinner card A will enter a further distance between the stencil cylinder C and the impression roller R before it is engaged by this couple than will a thicker card B. Accordingly, the leading line of print, positioned, say, at P on the cylinder, will be impressed a further distance from the leading edge of the thinner card A than from the leading edge of the thicker card B. Thus, when cards of various thicknesses are used, the registration of the printing on the cards will not be accurate, and bothersome and time-consuming adjustment must be made to the stencil on the cylinder to secure the registration desired. It is obvious from the foregoing that applicant's mechanism eliminates all of the objectionable features of an arrangement of the character diagrammatically shown in Fig. 6.

Applicant's invention also incorporates novel and improved means for delivering the cards to be printed, singly and successively, to exactly the same position for engagement by the printing couple and printing thereby, irrespective of variations in the thickness of the cards; incorporating also means for adjusting the mechanism in accordance with various lengths of cards, and means for adjusting a guide to obtain accurate adjustment of the printing on the card in a side-wise direction. By means of this mechanism, combined and synchronized with the card engaging mechanism, hairline registration of the printing on cards of variable thicknesses may be obtained, not only with respect to the forward edge of the card, but also with respect to its side edges and also as to horizontal alignment thereon.

In this connection, a suitable stationary plate or platform 50 is supported on the frame of the machine. This plate extends

well forward toward the printing couple. The forward feed of the cards into position for engagement by the printing couple is accomplished by means of a reciprocating table 51 mounted above platform 50. This table is supported on the upper ends of levers 52 fixed to a rock shaft 53, so that table 51 is reciprocated, as the rock shaft is rotated, for instance, by means of a link 54 connecting a lever 55 on shaft 53 to a lever 75 56, which is adapted to be rocked by a cam 57 rotating in synchronism with the stencil cylinder. Lever 56 is pivoted to a side frame of the machine at 58 and carries a pin or roller 59, which rides on the surface of cam 80 57. A spring 60 tends to maintain lever 52 and table 51 retracted.

Before explaining the synchronized movements of the card feed and card engagement mechanism, it may be mentioned that table 51 is composed of a lower plate 61, which is relatively stationary to lever 52, and an upper plate 62, which is mounted in grooved side plates 63 and 64 on plate 61, so as to be adjustable thereon by means of a screw 65, which engages an ear 66 on lower plate 61 and is threaded into a member 67 riveted to upper plate 62. By turning screw 65, plate 62 may be adjusted relatively to plate 61 and levers 52 so as to vary the position of the print on the forward edge of the card, and also to adjust the feed mechanism in accordance with cards of various lengths, so that the moment and position of engagement of each card by the printing couple will be always exactly the same.

Over plate 62 is a plate 68, which has an undercut flange 69 disposed across the front edge of table 51. Plate 68 is pivoted on a pin 70 carried on plate 62, and at its other side has a projection 71 provided with a slot 72, which is penetrated by a set screw 73 engaging plate 62. The front edge 69 of plate 68 may be adjusted into exact parallel alignment with the lines of print on the stencil sheet positioned on the stencil drum. Thus, when the rear edge of a card is placed closely against edge 69, the card will be aligned horizontally in parallel relation to the lines of print on the stencil. The recessed front edge 69 tends to hold the card flat as it is advanced to and engaged by the printing couple.

The table connection with levers 52 includes tabs 74 on plate 61, having pins 75 which rest in the notched upper ends of levers 52, and plates 76 are secured to levers 52 and press against tabs 74 to prevent disengagement of the pins 75 from the levers 52.

A spring 77, connected with the front edge of table 51, maintains the front edge of this table in contact with the platform 50, since table 51 is elevated at the back edge when the lever 52 oscillates, due to

the lever 52 being directly connected with the table 51.

Means are provided for adjusting the cards laterally with respect to platform 50 and table 51. These means include a gauge plate 80, which is carried on the end of a screw 81, the screw extending through to pins 82 and 83 fixed to plate 62, and confining between them a knurled nut 84, which 10 is in threaded engagement with screw 81. By turning knurled nut 84 in one direction or the other, the gauge 80 may be moved either right or left, and thus may be located to register the cards in a sidewise direction 15 properly with the sidewise disposition of the print on the stencil.

A plurality of spring fingers 85 are supported on a bracket 86 positioned on table 50. These fingers extend well toward the 20 printing couple, and have curved outer ends pressing downwardly on table 50, whereby the cards are restrained against the front edge of reciprocating table 51, and the cards are held flat, so that they will not rub 25 on the stencil as the cylinder and stencil rotate over the cards.

Of course, the mechanism just described for feeding the cards into the adjusted definite stationary position between the printing 30 couple for engagement thereby is synchronized with the other operating parts of the machine, including, obviously, the stencil cylinder. The operator places the card to be fed with its rear edge close against 35 the gauge 69 and in the recess thereof. The main crank handle of the machine is then turned to revolve the cylinder in printing direction, which is accompanied by rotation of cam 57. The rotation of this cam during 40 the turning of the cylinder to the point where further rotation of the cylinder is prevented by the pin 20 thereon engaging the lever 52 causes lever 52 to move the table 51 forwardly to advance the card into the 45 exact predetermined stationary position desired between the printing couple. The handle 36 is so positioned with respect to the main crank that, while the operator's hand still remains on the main crank handle, 50 he can reach the handle 36 with his thumb and depress the same, first, to release the impression roller to press upwardly against the card and cylinder while the card and cylinder are held stationary, and then, on 55 further depressing handle 36, to release the cylinder for rotation and accomplish the delivery and printing of the card thereby. At the point where the cylinder is released from the detent for rotation, the contour of cam 60 57 is silent, or a true curve, and will hold the card at a standstill in the exact printing position desired, so that no movement of the table 51 transpires to vary the position of the card with respect to the cylinder during 65 or after its engagement by the printing

couple. The line of print on the cylinder should be set over the card in an equally exact position.

If it is desired to bring the print further from or nearer to the leading edge of the card, a corresponding adjustment is made of plate 62 on table 51 by means of screw 65. If the sidewise location of the printing on the card is desired to be changed, the gauge 80 is adjusted accordingly by means of nut 75 84. If the lines of print on the card are not exactly parallel with the leading edge of the card, plate 68 is pivotally adjusted on plate 62 of table 51 by means of set screw 73.

It will be apparent from the above that with a machine having mechanism of the type described above hair line registration of print may be obtained on cards of variable thickness. The invention, however, is not restricted to the precise construction which has been described above for the purpose only of illustrating the invention, and accordingly, as many changes could be made in the above construction and various different embodiments of this invention could be made without departing from the scope thereof, it is understood that all matter contained in the above description or shown in the accompanying drawings shall be interpreted as illustrative and not in a limiting sense.

What I claim is:—

1. In an apparatus of the character described, in combination, a printing couple, means for holding the members of the printing couple separated, means for positioning a card between the printing couple, and means for bringing the printing couple together to engage the card after the card has been positioned therebetween. 105

2. In an apparatus of the character described, in combination, a printing couple, means for holding the members of the printing couple separated, means for positioning a card between the printing couple, means for bringing the printing couple together to engage the card after the card has been positioned therebetween, and means for holding one member of the printing couple stationary while the card is initially engaged by the couple. 110

3. In an apparatus of the character described, in combination, a printing couple, means for holding the members of the printing couple separated, means for actuating the printing couple, mechanism synchronized with said actuating means for delivering a card to a certain predetermined position between the separated printing couple, and means for bringing the printing couple together to engage the card while the card is stationary in said position. 120

4. In an apparatus of the character described, in combination, a rotatable printing cylinder, a coacting impression roller, means 125

- for rotating the cylinder, means for stopping and holding the cylinder in a definite predetermined position, means for holding the impression roller separated from the cylinder when in said position, and means controlled by the operator for releasing the roller to press against the cylinder while in said position to engage work therebetween.
5. In an apparatus of the character described, in combination, a rotatable printing cylinder, a coacting impression roller, means for rotating the cylinder, means for stopping and holding the cylinder in a definite predetermined position, means for holding the impression roller separated from the cylinder when in said position, means controlled by the operator for releasing the roller to press against the cylinder while in said position to engage work therebetween, and means under the control of the operator for subsequently releasing the cylinder for rotation to deliver and print work engaged by the printing couple.
6. In an apparatus of the character described, in combination, a rotatable printing cylinder, a coacting impression roller, means for rotating the cylinder, means for stopping and holding the cylinder in a definite predetermined position, means for holding the impression roller separated from the cylinder when in said position, means controlled by the operator for releasing the roller to press against the cylinder while in said position to engage work therebetween, and means under the control of the operator for subsequently releasing the cylinder for rotation to deliver and print work engaged by the printing couple, said means including a handle and mechanism connecting the handle with the impression roller and cylinder whereby when said handle is moved in a certain direction the impression roller is first released and subsequently the cylinder is released.
- 45 7. In an apparatus of the character described, in combination, a rotatable printing cylinder, a coacting impression roller, means for rotating the cylinder, means for stopping and holding the cylinder in a definite predetermined position, means for holding the impression roller separated from the cylinder when in said position, means controlled by the operator for releasing the roller to press against the cylinder while in said position to engage work therebetween, and means under the control of the operator for subsequently releasing the cylinder for rotation to deliver and print work engaged by the printing couple, said means including a handle and mechanism connecting the handle with the impression roller and cylinder whereby when said handle is moved in a certain direction the impression roller is first released and subsequently the cylinder is released, feed mechanism synchronized with
- the rotation of the cylinder whereby cards are placed in a definite predetermined stationary position between the cylinder and roller while separated, the roller moving to engage each card between it and the cylinder while each card and the cylinder are stationary.
8. In an apparatus of the character described, in combination, a rotatable stencil cylinder, detent means for stopping rotation of the cylinder in a definite position on each revolution thereof, an impression roller coacting with the cylinder, mechanism operating to place and hold the roller separated from the cylinder whenever the cylinder is stopped in said position, and means under the control of the operator whereby the roller may be released to press against the cylinder while the cylinder is held stationary by said detent means.
- 10 9. In an apparatus of the character described, in combination, a rotatable stencil cylinder, detent means for stopping rotation of the cylinder in a definite position on each revolution thereof, an impression roller coacting with the cylinder, mechanism operating to place and hold the roller separated from the cylinder whenever the cylinder is stopped in said position, and means under the control of the operator whereby the roller may be released to press against the cylinder while the cylinder is held stationary by said detent means, and whereby the cylinder detent means may be released by the operator to permit rotation of the cylinder subsequent to the release of the roller.
- 15 10. In combination with a printing couple comprising a rotary printing cylinder and a coacting impression roller, latch mechanism for holding the roller separated from the cylinder, a handle connected with said latch mechanism whereby the operator may operate the latch mechanism to release the impression roller, and means normally acting to press the roller against the cylinder, said latch mechanism including a rock shaft, arms on the shaft connected with the roller to depress the same, a stop lever on said shaft, and a roll stop shaft cradle engaging said stop lever to prevent rocking of said rock shaft and movement of said arms in a direction permitting the roller to rise against the cylinder.
- 20 11. In an apparatus of the character described, in combination, a rotatable printing cylinder having a stop pin thereon, a pivoted detent lever adapted to be engaged by said pin to stop rotation of the cylinder in a predetermined position, a pivotally mounted impression roller coacting with the cylinder, means including a latch device for maintaining the roller depressed from the cylinder, a rotatable shaft, and connections between said shaft and said detent mechanism and latch device whereby upon rota-
- 25 30 35 40 45 50 55 60 65 70 75 80 85 90 95 100 105 110 115 120 125 130

tion of said shaft in a predetermined direction first the latch device is retracted to release the roller to engage work positioned between it and the cylinder, and subsequently the detent lever is withdrawn from the cylinder stop pin to permit rotation of the cylinder.

12. In an apparatus of the character described, in combination, a rotatable printing cylinder having a stop pin thereon, a pivoted detent lever adapted to be engaged by said pin to stop rotation of the cylinder in a predetermined position, a pivotally mounted impression roller coacting with the cylinder, means including a latch device for maintaining the roller depressed from the cylinder, a rotatable shaft, and connections between said shaft and said detent mechanism and latch device whereby upon rotation of said shaft in a predetermined direction first the latch device is retracted to release the roller to engage work positioned between it and the cylinder, and subsequently the detent lever is withdrawn from the cylinder stop pin to permit rotation of the cylinder, said connections including a gear loose on said shaft meshing with a gear connected to the cylinder detent lever, said loose gear having a notched hub, a pin se-

cured to the shaft and disposed in the notches of said gear hub, and a train of levers connecting said shaft with said latch.

13. In an apparatus of the character described in combination, card feed mechanism including a card feeding table, an oscillating lever secured to the table to reciprocate the same horizontally, a rotatable cam connected with said lever whereby the lever is oscillated in accordance with the rotation of the cam, a printing couple including a rotatable printing cylinder, and means for rotating the cylinder and said cam in synchronism.

14. In an apparatus of the character described, in combination, printing mechanism, card feed mechanism, and means coordinating the operation of the card feed mechanism with the operation of the printing mechanism, said card feed mechanism including a card feeding table, an oscillating lever secured to the table to reciprocate the same horizontally, and a rotatable cam connected with said lever whereby the lever is oscillated in accordance with the rotation of the cam.

This specification signed this 31st day of January, 1927.

ERNEST J. BRASSEUR.
